UNITED STATES PATENT OFFICE.

ERNEST ERICKSON, OF CLAIRTON, AND CHARLES R. JEFFREYS, OF MCKEESEPORT,
PENNSYLVANIA.

CENTRIFUGAL DRIER.

Application filed July 26, 1922. Serial No. 577,511.

To all whom it may concern:

Be it known that we, ERNEST ERICKSON and CHARLES R. JEFFREYS, citizens of the United States, and residents of Clairton and 5 McKeessport, respectively, in the county of Allegheny and State of Pennsylvania, have invented certain new and useful Improvements in Centrifugal Driers, of which the following is a specification.

10 This invention relates to centrifugal driers and more particularly, to the baskets for said driers, and has for one of its objects the provision of an improved basket construction having a removable screen 15 which may be removed without taking the basket out of its operating position.

Heretofore when it was desired to replace the screen in centrifugal drier baskets, it was necessary to dismantle the drier and 20 move and dismantle the basket, while with the present construction the screen can be replaced without removing the basket from its operating position, thus reducing the labor of such an operation eighty per cent.

25 Another object is to provide a basket for centrifugal driers having the novel construction and combination of parts herein-after described and illustrated in the accompanying drawings.

30 In the drawings, Figure 1 is a side elevation partly in section showing a centrifugal drier having this invention embodied therein.

Figure 2 is an enlarged fragmentary sectional elevation through a drier basket constructed in accordance with this invention.

Referring particularly to the drawings, the numeral 2 designates the basket holder in which the basket A is revolvably mounted. The basket A is keyed or otherwise secured to a central spindle or shaft 3 journaled in the supporting arm 4 of the machine, and having a drive pulley 5 on its upper end. The pulley 5 receives its power 45 from a prime mover, such as the steam engine 6 having a drive pulley 7, and connected with the pulley 5 by a belt 8.

The basket A comprises a bottom wall or base 9 having a centrally arranged shaft receiving tapered socket 10 for the reception of shaft 3, and having a depending annular flange 11 to which the side wall 12 is secured. The upper face of the bottom 55 9 is cut away around its edge forming an annular recess 13 for a purpose to be described.

The side wall 12 is provided with spaced perforations 14 and is riveted or otherwise permanently and rigidly secured to the depending flange 11 of the bottom 9.

60 The upper end of the side wall is provided with an outwardly flaring flange 15 preferably formed by securing an angle iron around the same.

A conical shaped top member 16 having an annular flange 17 paralleling and overlying the flange 15 on the side wall is removably secured to the flange 15 by stud bolts 18 screwed into suitable apertures 19 in the flanges 15 and projecting through suitable apertures 20 in the flange 17 of the 70 top 16, and having nuts 21 and 22 threaded for locking them in position in the flange 15, and for holding the top 16 in position, respectively.

A wire mesh drying screen 23 is arranged 75 around the inner periphery of the side wall 12 and has its longitudinal or vertical edges overlapped as at 24 to form a loose joint. A perforated supporting plate 25 is arranged around the inner periphery of the 80 screen 23 and has its edges overlapped as at 26 to form a loose joint.

The lower ends of the screen 23 and plate 25 are mounted in the recess 13 formed around the bottom 9 and their upper ends 85 are clamped in position by a clamping ring B, which has a downwardly and inwardly flaring flange 27 overlying the upper ends of the screen 23 and plate 25, and an outwardly extending flange 28 fitted between 90 the flange 15 of the side wall 12 and the flange 17 of the top 16. The flange 28 of the ring B is provided with apertures 29 registering with the apertures in the flanges 15 and 17 for the reception of the stud 95 bolts 18.

In operation when the screen 23 becomes fouled or when, for any other reason, it is desired to replace or repair it, it is only necessary to loosen the nuts 22 and remove 100 the top member 16 and ring B, then lift out the screen 23 and insert a new one or repair and replace the old one.

The operation of replacing the screen is simple and requires a minimum of labor, 105 since the drier need not be removed from its operative position.

We claim:—

1. A basket for centrifugal driers comprising a dish-shaped imperforate bottom 110

wall, a perforated side wall permanently secured to said bottom wall, a top member removably mounted on said side wall, a wire mesh screen member extending around the inner periphery of said side wall, a perforated plate extending around the inner periphery of said wire mesh screen, said wire mesh and said perforated plate being mounted so that their vertical edges overlap, and having their lower ends mounted in a suitable recess in said bottom wall, and a clamping ring removably mounted between said top member and said side wall adapted to clamp said screen and perforated plate in position, said clamping ring being provided with a downwardly and inwardly flaring retaining flange overlying the upper ends of said screen and said plate.

2. A basket for centrifugal driers comprising a dish-shaped imperforate bottom wall, a perforated side wall permanently se-

cured to said bottom wall, a top member removably mounted on said side wall, a wire mesh screen member extending around the inner periphery of said side wall, a perforated plate extending around the inner periphery of said wire mesh screen, said screen and said perforated plate having their lower ends mounted in a suitable recess in said bottom wall, and a clamping ring removably mounted between said top member and said side wall adapted to clamp said screen and perforated plate in position, said clamping ring being provided with a downwardly and inwardly flaring retaining flange overlying the upper ends of said screen and said plate.

In testimony whereof we have hereunto set our hands.

ERNEST ERICKSON,
CHARLES R. JEFFREYS.
